UNITED STATES PATENT OFFICE

154,556

DESIGN FOR A COMBINATION COASTER AND ASH TRAY HOLDER

Charles Mankouski, Newport, N. Y.

Application September 13, 1948, Serial No. 148,574

Term of patent 14 years

(Cl. D85—2)

To all whom it may concern:

Be it known that I, Charles Mankouski, a citizen of the United States, residing at Newport, in the county of Herkimer and State of New York, have invented a new, original, and ornamental Design for a Combination Coaster and Ash Tray Holder, of which the following is a specification, reference being had to the accompanying drawing, forming part thereof.

I claim:

The ornamental design for a combination coaster and ash tray holder, as shown.

CHARLES MANKOUSKI.
